(54) **LEAD, WHITE**

(76) Inventor: **Homer Holland**

Thomas Holland.

Letters Patent.

The schedule referred to in these Letters Patent and making part of the same, containing a description in the words of the said Thomas Holland himself of his improvement in the process of oxidizing metallic lead and making carbonate of lead.

To all to whom these presents shall come: Be it known that, I, Thomas Holland of the Town of Westfield, County of Berkshire and State of Massachusetts, have invented a new and useful improvement in the process for oxidizing metallic lead & for making & purifying carbonate of lead or the pigment known as known by the name of white lead, which improvement has not heretofore been known or used & that the following is a full and exact description of said improvement, sufficiently distinguishing the same from all things before known as will be sufficient to enable any person skilled in the art or science of making & purifying the salts, acids & vitrals of lead, from any other than carbonate of lead to apply & use said improvement in the making & purifying of the same. The invention consists of:

I. An improvement in the method of applying the conjoint action of friction, air and water to metallic by placing fragments of this metal in revolving lead cylinders or chambers; so as to produce a fine powder or purified substance of lead, for making or purifying the common salts, vitrals & acetate of lead.

II. An combining carbonic acid from the atmosphere, directly with this powder, as it is formed in the cylinders by the action of carbonate of soda or other alkaline vitrals so as to produce or make the carbonate of lead or the pigment known as white lead. It effect the oxidation.

of the lead, spirit coarse shot or other fragments of mangled lead, into a wooden cylinder or chamber, about four feet in length and three feet in diameter, made to revolve, horizontally upon an axis of flanges. The wooden cylinder or chamber is enclosed in a strong and tight wooden case. Air is admitted by perforations of the cylinder at its ends, near the axis. Soft water is put in the chamber, sufficient to cover the charge of shot or fragments. The cylinder is made to revolve eighteen or twenty times in a minute, by the application of any force. The electro-chemical action of the friction and water, produces a fine pulpy substance of lead which is strained out by running along from the side of the cylinder & placing this in a hollow tube, leading to a wine or stream, resting in a basin or trough, which conduct to a reservoir.

This pulpy substance sufficiently freed from water, is readily combined with acetic acid, and giving "sugar of lead" mixed with nitric acid producing nitrate of lead.

To make carbonate of lead the process is identical with the above described for the suboxide - with the addition of about six or eight turns of the carbonate of soda to each gallon of water used in the cylinder. The cylinder is revolved several hours in producing the suboxide for the salts of lead and from twelve to sixteen, previous to staining out the carbonate or white lead; which is conducted as above described to a vessel, armed with agitators & washed by decantation with pure water, once or twice, to free it from alkali. When it is to be dried by any convenient means, becoming the pure carbonate or "bloom" white lead of commerce. In this process for white lead, the use of wings & of acetic or carbonic acid in any shape, is avoided & the health of the manufacturer is preserved from the fumes of the volatile pyrocarbonate of lead so deadly in the ordinary processes. The foregoing process applies; but the revolving chamber may be cylindrical, pyramidal or polygonal, of any size & length. The lead being

lining of a wooden cylinder may be of sheet lead or cast iron, extended to fit the wooden case or case so it will be convenient when time comes to fit away. The number of cylinders their weight and the charge, will depend on the force employed and the intent of the manufacturer. Each cylinder (principally the lead chamber) may weigh six hundred pounds. The charge added from ammonia is one hundred fifty pounds fragments & the necessary water and carbonate of soda. The lead fragments may be sheets of sheet lead, shot or fragments, produced by, crushing melted lead the fragments into water, shot, iron and other alloys of metals are often mingled with lead in the shot of ammonia & unfit them for this purpose.

The alkali, before it is soda, as this has the strongest affinity or attraction for copper & carbonic acid & is capable to form an hydrate. The pulpy carbonate may also be conveniently prepared in the vessel employed for decomposition, as it is mixed with an inciter; by passing into the pulpy carbonate, as with drama, fine carbonic acid is produced by combustion of drama, from decomposition or from the decomposition of carbonate of lime or chalk, by sulphuric or hydrochloric acid. The decomposing vessel, again may be used conveniently in removing a disagreeable yellowish of pure carbonated lead, by means of mixing of a little of indigo or blue chalk with the carbonate of lead. Retains as my invention & improvement.

1st. The application of the following cylinders or chambers as above described, to the filling, communication, amalgamation & connecting of metals to and into the fine pulpy carbonate of lead, for the sake, acetate & nitrate of lead or carbonate of lead.

2nd. The amalgamating of the above described cylinders & vessels formed in the cylinders by the addition of an alkaline carbonate & by passing into this pulpy acetate, carbonic acid, giving immediately white lead.

Witness
Wm. Hooker Jr.
Boston Mass.
